UNITED STATES PATENT OFFICE

2,264,532

HYDRAULIC CIRCUIT FOR MACHINE TOOLS

Paul S. Jackson, Rockford, Ill., assignor to Rockford Machine Tool Company, Rockford, Ill., a corporation of Illinois

Application June 6, 1939, Serial No. 277,651

9 Claims. (Cl. 90—34)

This invention relates generally to machine tools having a support actuated by a piston and cylinder device, such as planers, shapers, etc., and more particularly to a device associated with the hydraulic circuit of such piston and cylinder device for the purpose of eliminating chatter of the support on its ways when operated at low speeds. It is the general object of the invention to provide a new and improved mechanism for eliminating such chatter.

Although liquids are generally characterized as solid bodies and non-compressible, it has been found in hydraulic circuits for machine tools that there is an appreciable compression of the oil, especially when used in large volumes, as is required in the long cylinders of large metal planers. This compressibility is frequently due to air which is entrained in the liquid, generally oil, either in a dissolved state or a slightly foamy condition. The use of a lubricating oil as the fluid medium in hydraulic circuits for machine tools is generally accepted, but the presence of air in the oil is a continuous source of annoyance and prevents smooth operation of the reciprocating support that is driven directly by the oil operating in a piston and cylinder device. The compressibility of the oil is evident, particularly on heavy loads and at slow speeds, such as from twenty feet and less per minute. Apparently, during such heavy cuts the air in the oil is compressed to a certain point before the resistance of the tool on the work is overcome, whereupon the table lunges forward and the pressure of the oil drops, this cycle being repeated at a relatively high rate on light machines, and at a relatively low rate on heavy machines. Although at higher cutting speeds, such as those above thirty feet per minute, this action of the table on its ways apparently does not exist and the accompanying chatter is absent, the chatter at the lower speeds and on heavy loads is extremely objectionable.

Another object is to provide a new and improved hydraulic circuit with a compensating device which is operable to eliminate such chatter of the driven support. During the operation of the machine, this compensator functions to maintain the pressure in the hydraulic circuit constant so that a very smooth cut of the tool is obtained.

Another object is to provide in a hydraulic circuit for a machine tool support having a main piston and cylinder actuating the support, a hydraulic circuit including said cylinder and a compensating device comprising an auxiliary piston

and cylinder having one end of the cylinder connected to said hydraulic circuit adjacent one end of the main cylinder and having in the other end of the auxiliary cylinder a coil spring or other resilient element for resisting movement of the auxiliary piston therein when subjected to the fluid pressure of the hydraulic circuit.

Other objects will become readily apparent from the following detailed description taken in connection with the accompanying drawing, in which the figure illustrates a preferred form of the invention associated with the platen of a metal planer.

While I have illustrated in the drawing and shall hereinafter describe in detail a detailed form of the invention with a metal planer, it is to be understood that I do not intend to limit the invention to the particular form and arrangement shown, it being contemplated that various changes may be made by those skilled in the art without departing from the spirit and scope of the appended claims.

As illustrated in the drawing, numeral 10 represents platen or table of a planer on which a work piece 11 is secured in position to be cut by a suitable tool 12, the supporting means for which is not illustrated. The table is arranged to be reciprocated by means of a main piston and cylinder device having a cylinder 13 suitably supported on the bed of the machine (not shown) and a piston 14. The piston 14 is secured to one end of a piston rod 15, the other end of which extends out through one end of the cylinder and is secured to a depending portion 16 of the table 10 by means including a nut 17.

The invention contemplates the reciprocation of the table 10 by means of a fluid, such as oil under pressure, the table generally being moved at a slow or feed rate toward the left during a cutting operation, and at a higher or traverse rate toward the right during the return stroke. The hydraulic circuit includes the main piston and cylinder device 13, 14, heretofore mentioned, a pumping mechanism 18 and valve mechanism

45 designated generally 19. The pumping mechanism 18 and valve mechanism 19 may be of any one of a number of commercial products as, for example, a type D-R pump manufactured by The Oilgear Company of Milwaukee, Wisconsin. 50 This pump consists generally of a tank or reservoir 20 on which the pump casing 21 is mounted, the pump casing having amongst other mechanisms, a gear type pump 22 and a variable displacement piston type pump. Since the construction of the pumping mechanism 18 forms no

part of the present invention, it will suffice to say that 23 indicates a means for adjusting the speed of the table during its cutting stroke toward the left, 24 indicates a means for adjusting the speed of the table during its return stroke toward the right, 25 indicates an automatic constant pressure relief valve in the return line to the tank 20, and 26 indicates a high pressure relief valve in a return line to the tank 20. The output of the gear pump 22 is conducted to the valve mechanism 19 through a conduit 30, whereas the high pressure fluid from the variable displacement piston pump of the mechanism 18 is conducted to the valve mechanism by a conduit 31. The right hand end of the main cylinder 13 is connected to the valve mechanism 19 by means of a conduit 32, and the left hand end of the cylinder 13 is connected to the valve mechanism 19 by means of a conduit 33. A conduit 34 forms a return from the valve mechanism to the tank 20, and a conduit 35 forms a return from the valve mechanism to the pumping mechanism 18. A conduit 36 connects at one end to the valve mechanism 19 and at the other end to the pumping mechanism 18, and functions to supply fluid to internal parts of the pumping mechanism when it is desired to obtain the maximum stroke of the variable stroke pump therein. The operation of the valve mechanism is controlled by means of a pilot having an operating member 40. This operating member is connected to one end of a lever 41 pivoted at 42, the other end of the lever being connected by means of a rod 43 to one arm 44 of a bellcrank device pivotally supported at 45. The other arm 46 of the bellcrank carries a roller 47 positioned to be acted upon by a cam or dog 48 secured to the table 10 or by a cam or dog 49 secured thereto, the dogs being effective at the ends of the cutting and return strokes, respectively, to cause reversal of the table by actuation of the pilot valve.

More particularly, the invention in the form disclosed herein includes the provision of a means or compensating device 60 for eliminating chatter of the table on its ways when operating at relatively slow speeds. This compensating device comprises an auxiliary cylinder 61 having an auxiliary piston 62 therein. The right hand end 64 of the cylinder is connected to the hydraulic circuit by means of a conduit 65 which communicates with the conduit 33 adjacent the left hand end of the main cylinder 13. A resilient means in the form of a conically coiled spring 63 is positioned in the left hand end of the auxiliary cylinder 61 to resist movement of the piston 62 toward the left when subjected to the pressure of the fluid in the hydraulic circuit. In order to provide for adjustment of the resistance exerted by the coiled spring 63, a screw device 66 is threaded through the right hand end wall of the cylinder 61 and carries a cup-shaped member 67, between which and the piston 62 a coiled spring 68 is positioned.

Under certain circumstances and in order to obtain an elimination of chatter in both directions of operation of the table, a similar compensating device 50 may be provided for the right hand end of the main cylinder 13. This compensating device comprises an auxiliary cylinder 51 having an auxiliary piston 52 therein. The left hand end 53 of the cylinder is connected to the hydraulic circuit by means of a conduit 54 which communicates with the conduit 32 adjacent the right hand end of the main cylinder 13. A resilient means in the form of a

a coiled spring 55 is positioned in the right hand end of the auxiliary cylinder 51 to resist movement of the piston 52 toward the right when subjected to the pressure of the fluid in the hydraulic circuit. Preferably, a piston rod 56 is connected to the piston 52 when it is desired to observe the action of the piston 52 from a point externally of the cylinder. In order to avoid any build up of pressure in the right hand end of the cylinder 51 and the left hand end of cylinder 61 due to leakage of fluid past the pistons therein, a return conduit 51' is provided for the cylinder 51 and a return conduit 61' is for the cylinder 61. These conduits serve to drain the portions of the auxiliary cylinders to which they are connected.

In order to permit the use of one compensating device or the other, or both, a suitable valve 65' is provided in the conduit 65 and a valve 54' in the conduit 54 to permit of closing or opening said conduits. In practice, it is desirable that the conduits between the compensating device cylinders and main cylinder 13 be as short as possible. In the event only one compensating device is used, it is preferable to use the one connected to that end of the main cylinder which is emptying during the cutting operation.

As mentioned hereinbefore, the preferred form 30 of the invention is embodied in a hydraulic circuit for actuating the table of a metal planer. Such machine tool generally has a mechanism for feeding the tool 12 laterally of the work at the beginning of each stroke. This may be accomplished by suitable means well known in the art, including a piston and cylinder device 19.

In operating the circuit disclosed herein, fluid is first supplied to the right hand end of the cylinder 13 for moving the table toward the left through a cutting stroke during which the fluid from the left hand end of the cylinder 13 passes back through the conduit 33 and valve mechanism 19, thence through conduit 35 to the pumping mechanism 18. A portion of the fluid passing through conduit 35 continues downwardly into the tank 20 past the automatic constant pressure relief valve 25, whereas the remainder of this fluid passes to the intake of the pumping mechanism so that only an amount of fluid equivalent to the volume of the piston rod 15 is caused to pass over the automatic constant pressure relief valve 25. Upon completion of the cutting stroke, the dog 48 engages the roller 47 so as to actuate the pilot valve member 40, whereupon the valve mechanism 19 is conditioned to direct fluid to the left hand end of the cylinder 13 through conduit 33 for the purpose of effecting a return stroke of the table 10. Fluid from the right hand end of the cylinder 13 then passes out through the conduit 32 to the valve mechanism 19. The valve mechanism is then adjusted so as to connect the adjacent ends of the conduits 32, 33 and 31, so as to obtain a fast return stroke of the table through the differential action thus obtained. The table continues in its return stroke toward the right until the dog 49 thereon engages the roller 47 and pivots the bellcrank in a counterclockwise direction to effect a cutting stroke toward the left. The table continues to reciprocate until the operator manipulates a stop valve 75 provided in the valve mechanism 19.

In practice, it has been found that the mechanism herein disclosed effectively eliminates chatter. Furthermore, the compensating devices

operate to cushion the reversals of the table, as well as the movement of the table in the event "hard spots" are encountered in the work by the tool. The invention has been particularly effective in connection with heavy tables or heavily loaded tables when operated at slow speeds, such as twenty feet per minute or less in planers. Under such conditions, when heavy cuts are being taken, the oil in the hydraulic circuit or the air entrain therein compresses to a certain point where the resistance of the tool is overcome and then the table lunges ahead, whereupon the pressure of the oil and any entrained air drops, whereupon the table will momentarily stop until the necessary pressure is again built up. The rate at which this oscillation occurs is dependent to a considerable extent upon the weight of the reciprocating table, oscillations and the attendant vibration of the table is effectively eliminated by the invention disclosed herein. This is accomplished by means of the compensator device because the piston thereof will oscillate in the auxiliary cylinder so as to maintain the pressure in the hydraulic circuit substantially constant and maintain a regular fluid flow from the pumping mechanism to the main cylinder.

A second compensating device may be incorporated when it is desired to effect smooth operation during the return stroke of the table, as well as during the cutting stroke. When this compensating device is connected in the circuit, it has been found desirable to close the automatic constant pressure relief valve 25 entirely, with the result that any return flow of oil in excess of that passing through the intake of the pumping mechanism returns to the tank 20 over the hydraulic pressure relief valve 26.

I claim as my invention:

1. In a metal planer having a table, a main piston and cylinder device for actuating said table and a hydraulic circuit including pumping mechanism and valve mechanism for supplying and controlling the flow of fluid to and from the opposite ends of said cylinder, in combination, a compensating device comprising an auxiliary cylinder, a piston therein, a conduit connecting one end of said cylinder with said hydraulic circuit adjacent one end of said main cylinder and a spring in the other end of said auxiliary cylinder for resisting movement of the piston therein.

2. In a metal planer having a table, a main piston and cylinder device for actuating said table and a hydraulic circuit including pumping mechanism and valve mechanism for supplying and controlling the flow of fluid to and from the opposite ends of said cylinder, in combination, a compensating device comprising an auxiliary cylinder, a piston therein, a conduit connecting one end of said cylinder with said hydraulic circuit adjacent one end of said main cylinder and resilient means in the other end of said auxiliary cylinder for resisting movement of the piston therein.

3. In a metal planer having a table, a main piston and cylinder device for actuating said table and a hydraulic circuit including pumping mechanism and valve mechanism for supplying and controlling the flow of fluid to and from the opposite ends of said cylinder, in combination, a compensating device comprising an auxiliary cylinder, a piston therein, means connecting one end of said cylinder with said hydraulic circuit so as to subject the piston therein to the pressure of the fluid supplied to said main cylinder and resilient means in the other end of said auxiliary

cylinder for resisting movement of the piston therein.

4. In a metal planer having a table, a main piston and cylinder device for actuating said table and a hydraulic circuit including pumping mechanism and valve mechanism for supplying and controlling the flow of fluid to and from the opposite ends of said main cylinder, in combination, a first compensating device comprising an auxiliary cylinder, a piston therein, means connecting one end of said cylinder with said hydraulic circuit adjacent one end of said main cylinder, resilient means in the other end of said auxiliary cylinder for resisting movement of the piston therein, and a second compensating device comprising a cylinder, a piston therein, resilient means in one end of said last mentioned cylinder for resisting movement of the piston therein, and means connecting the other end of said cylinder to said hydraulic circuit adjacent the other end of said main cylinder.

5. In a metal planer having a table, a main piston and cylinder device for actuating said table and a hydraulic circuit including pumping mechanism and valve mechanism for supplying and controlling the flow of fluid to and from the opposite ends of said cylinder, in combination, a compensating device comprising an auxiliary cylinder, a piston therein, a conduit connecting one end of said cylinder with said hydraulic circuit adjacent the end of said main cylinder from which fluid discharges during a cutting operation, and a spring in the other end of said auxiliary cylinder for resisting movement of the piston therein.

6. In a metal planer having a table, a main piston and cylinder device for actuating said table and a hydraulic circuit including pumping mechanism and valve mechanism for supplying and controlling the flow of fluid to and from the opposite ends of said cylinder, in combination, a compensating device comprising an auxiliary cylinder, a piston therein, a conduit connecting one end of said cylinder with said hydraulic circuit adjacent one end of said main cylinder, and means for draining fluid from the end of the auxiliary cylinder in which the resilient means is located.

7. In a metal planer having a table, a main piston and cylinder device for actuating said table and a hydraulic circuit including pumping mechanism and valve mechanism for supplying and controlling the flow of fluid to and from the opposite ends of said cylinder, in combination, a compensating device comprising an auxiliary cylinder, a piston therein, a conduit connecting one end of said cylinder with said hydraulic circuit adjacent one end of said main cylinder, and means for adjusting the tension of said spring.

8. In a metal planer having a table, a main piston and cylinder device for actuating said table and a hydraulic circuit including pumping mechanism and valve mechanism for supplying and controlling the flow of fluid to and from the opposite ends of said cylinder, in combination, a compensating device comprising an auxiliary cylinder, a piston therein, a conduit connecting the head end of said cylinder with said hydraulic circuit adjacent one end of said main cylinder, a spring in the other end of said auxiliary cylinder for resisting movement of the piston therein, and means for adjusting the tension of said spring comprising a screw device threaded through the end wall of the head end of the auxiliary cylinder and a coiled spring positioned between the inner

end of said screw device and the piston in the auxiliary cylinder.

9. In a metal planer having a table, a main piston and cylinder device for actuating said table and a hydraulic circuit including pumping mechanism and valve mechanism for supplying and controlling the flow of fluid to and from the opposite ends of said main cylinder, in combination, a first compensating device comprising an auxiliary cylinder, a piston therein, means connecting one end of said cylinder with said hy-

draulic circuit adjacent one end of said main cylinder, resilient means in the other end of said auxiliary cylinder for resisting movement of the piston therein, and a second compensating device 5 comprising a cylinder, a piston therein, resilient means in one end of said last mentioned cylinder for resisting movement of the piston therein, and a valve device in each of the connecting means between the cylinders of the compensating devices and the hydraulic circuit.

PAUL S. JACKSON.
